UNITED STATES PATENT OFFICE

JAMES L. NORRIS, OF WASHINGTON, DISTRICT OF COLUMBIA, ADMINISTRATOR OF WILLIAM PALLISER, DECEASED.

COMPOSITE GUN.

SPECIFICATION forming part of Letters Patent No. 269,100, dated December 12, 1882.

Application filed July 19, 1882. (No model.) Patented in England June 2, 1881, No. 2,425.

To all whom it may concern:

Be it known that I, JAMES L. NORRIS, a citizen of the United States, residing at Washington, in the District of Columbia, am in possession of an invention for a new and useful Improvement in Composite Guns, invented by WILLIAM PALLISER, (for which Letters Patent for Great Britain, No. 2,425, dated June 2, 1881, were obtained by WILLIAM PALLISER,) 10 of which the following is a specification.

This invention relates to the construction of heavy guns, which may be either breech-loaders or muzzle-loaders, as I will describe, referring to the accompanying drawings, of 15 which—

Figure 1 is a longitudinal section of a breech-loader according to my invention.

I cast in steel a casing, C, which constitutes the external material of the gun, extending its 20 whole length, and having the trunnions cast in one piece with it. I thoroughly anneal this casing, in order to equalize the strains resulting from its cooling, and I turn it on the outside and bore it internally nearly to the dimensions suited to receive the lining-tubes.

As the removal of metal by this turning and boring is apt to disturb the equilibrium of the internal strains, I again anneal the casing, so as to equalize these strains, and then, 25 by a light cut, finish the boring to the required dimensions and cut the internal screw-thread to receive the lining-tubes. These tubes are of soft iron, coiled, and arranged as follows: The inner lining-tube, A, extends from 30 the muzzle nearly to the breech, and it is thickened externally near the middle of its length, the thickened part terminating in rounded sloping shoulders *a b*, the front one of which, *a*, is by inserting the tube from the 35 breech, brought to fit a corresponding sloping shoulder in the bore of the casing. The hinder shoulder, *b*, is nearly in line with the front of the trunnions, and against this bears the outer lining-tube, B, into which the inner 40 tube, A, is introduced from the front. The tubes A and B are together introduced from the breech into the casing C, and screwed in

until the front shoulder, *a*, of the A tube and the rounded sloping end of the B tube bear respectively against the shoulders in the casing. 50

It is to be understood that the A and B tubes are not made a tight fit to one another or to the casing, as is usually done by shrinking the one part over the other. On the contrary they are made an easy fit at first, and 55 then, when the gun is used, the tubes being of comparatively yielding material, are to a certain extent expanded by the pressure of the powder-gas, and are thus caused to fit closely.

When the gun is to be used as a breech-loader the breech is arranged as shown in Fig. 1. A short outer tube, D, with a concave face, is screwed up against the convex end of the B tube, and within the tube D a short inner tube, E, with a projecting lip, is screwed 60 in, its lip extending over an internal lip formed at the end of the A tube, so that the joint of the two tubes is thus covered. The tube E is screwed internally and coned out at the mouth to receive the removable breech-plug F, which may be of the kind shown in the drawings, folding back on a hinge, or of any other suitable kind.

When the gun is to be used as a muzzle-loader the breech is arranged as shown in Fig. 2, the end of the A tube having screwed into it a plug, H, which is cupped, so as to act as a gas-check. A short outer lining-tube, D, with a concave face, is screwed up against the convex end of the B tube, and into this 75 tube is screwed the breech-plug G, with its face bearing against the cupped plug H, and extending partly onto the end of the A tube, so as to cover the joint.

In order to steady and secure the A tube at the muzzle, a collar or ring, P, is screwed into the mouth of the casing up against a shoulder of the A tube.

Having thus described the nature of this invention and the best means I know of carrying it out in practice, I claim—

The composite gun herein described, consisting of the exterior cast-steel casing, C, having the interior sloping shoulder, the coiled

wrought-iron tube A, having an externally thickened portion near the middle of its length, which terminates in the front and rear shoulders, a and b, and the coiled wrought-iron tube 5 B, covering the breech end of the former tube and bearing against the rear shoulder, b, said parts being arranged in the described relation, for the purposes set forth.

In testimony whereof I have signed my name

to this specification before two subscribing witnesses.

JAMES L. NORRIS,
*Administrator of the estate of William Palliser,
deceased.*
